UNITED STATES PATENT OFFICE

140,302

DESIGN FOR A TRANSPORT AIRPLANE

Edward H. Heinemann and Leo J. Devlin, Los Angeles, Calif., assignors to Douglas Aircraft Company, Inc., Santa Monica, Calif.

Application August 26, 1940, Serial No. 94,636

Term of patent 7 years

(Cl. D71—1)

To all whom it may concern:

Be it known that we, Edward H. Heinemann and Leo J. Devlin, citizens of the United States and residents of Los Angeles, in the county of Los Angeles and State of California, have invented a new, original, and ornamental Design for a Transport Airplane, of which the following is a specification, reference being had to the accompanying drawings, forming part thereof:

Figure 1 is a top plan view of a transport airplane showing our new design.

Figure 2 is a front elevational view of the airplane depicted by Figure 1;

Figure 3 is a side elevational view of the airplane depicted by Figure 2, and wherein a landing gear is shown in the extended position; and

Figure 4 is a bottom perspective view of the airplane in flight.

This application is a continuation in part of our earlier application, Serial No. D—80,444, filed October 14, 1938.

We claim:

The ornamental design for a transport airplane, substantially as shown and described.

EDWARD H. HEINEMANN.
LEO J. DEVLIN.
